Patented Nov. 11, 1975

237,640

GAME PUZZLE

William H. Baynes, Los Angeles, Calif.
(4122 Greenbush Ave., Sherman Oaks, Calif. 91403)

Filed Feb. 27, 1974, Ser. No. 446,528

Term of patent 14 years

Int. Cl. D21—01

U.S. Cl. D34—15 M

FIG. 1 is a top plan view of my new design for a game puzzle;

FIG. 2 is an end elevational view thereof; and

FIG. 3 is a perspective view thereof.

I claim:

The ornamental design for a game puzzle, substantially as shown and described.
